UNITED STATES PATENT OFFICE.

JAMES F. O'SHAUGHNESSY, OF NEW YORK, N. Y., ASSIGNOR TO THE UNITED STATES COTTON SEED COMPANY, OF SAME PLACE.

METHOD OF TREATING COTTON-SEED.

SPECIFICATION forming part of Letters Patent No. 298,617, dated May 13, 1884,

Application filed October 13, 1883. (No specimens.)

To all whom it may concern:

Be it known that I, JAMES F. O'SHAUGHNESSY, of New York, in the county of New York and State of New York, have invented 5 a new and useful Method of Treating Cotton-Seed; and I do hereby declare that the following is a full, clear, and exact description of the same.

My invention relates to an improved method 10 of treating cotton-seed for the purpose of obtaining its products at less expense in better condition.

Heretofore, as is well known, cotton-seed has been crushed with the hull and kernel together, and the oil expressed. This process 15 requires that the hull, which contains no oil whatever, shall be subjected to the same amount of compression as the kernel itself, which alone contains the oil. The food product, which has 20 to the mixed hull and kernel, is in good condition for its purpose; but the oil is rendered darker by reason of the presence of the hull in the compressed mixture.

It has also been common to hull the American upland seed and crush only the kernel, and to burn the hull with the adhering lint as fuel. This avoids the discoloration of the oil 25 caused by pressing the hull; but the food product—that is to say, the pure kernel—is lacking in an element required to make it a proper food for cattle to be fed by itself—that is to say, it lacks the hull, which, when ground with the kernel, makes a better and more wholesome food.

My invention therefore consists in the method 30 of treating cotton-seed by taking the hull separated from the kernel and grinding it, in removing the fiber therefrom, and then mix-

ing the ground hull with the crushed and pressed kernel, as hereinafter more particularly described and claimed.

I grind the hull separately, and when it contains fiber I separate the fiber therefrom in the manner described in Letters Patent No. 286,553, granted me on the 9th day of October, 1883. After thus grinding the hull and separating the fiber, which is unfit for food, but is valuable for other purposes, I mix the ground hull with the kernel from which the oil has been expressed, and form therefrom the food product. I thus obtain the fiber, the food product in its best form, and the oil in its best condition, and without any of the discoloration arising from the compression with the hull.

The various steps in the operation may be carried on by well-known apparatus, any suitable mill being used for grinding the hull, any ordinary press for pressing the kernel, and the fiber may be removed from the ground hull by any suitable winnowing or sifting apparatus.

I claim—

The herein-described method of treating cotton-seed, consisting in taking the hull separated from the kernel and grinding it, in removing the fiber therefrom, and then mixing the ground hull with the crushed and pressed kernel, all substantially as described.

In testimony whereof I have signed my name to this specification in the presence of two subscribing witnesses.

JAMES F. O'SHAUGHNESSY.

Witnesses:

WILLIAM F. MOODY,
V. S. LILLIE.

Correction in Letters Patent No. 298,617.

It is hereby certified that in Letters Patent No. 298,617, granted May 13, 1884, upon the application of James F. O'Shaughnessy, of New York, New York, for an improvement in "Method of Treating Cotton Seed," the name of the assignee was written and printed "United States Cotton Seed Company;" that said name should have been written and printed *United States Cotton Seed Cleaning Company*; and that the proper correction has been made in the files and records pertaining to the case in the Patent Office, and should be read in the Letters Patent to make the same conform thereto.

Signed, countersigned, and sealed this 20th day of May, A. D. 1884.

[SEAL.]

M. L. JOSLYN,
Acting Secretary of the Interior.

Countersigned:

BENJ. BUTTERWORTH,
Commissioner of Patents.
